UNITED STATES PATENT OFFICE.

LEWIS M. CLEMENT, OF MOUNTAIN LAKES, NEW JERSEY, ASSIGNOR TO WESTERN ELECTRIC COMPANY, INCORPORATED, OF NEW YORK, N. Y., A CORPORATION OF NEW YORK.

RADIO RECEIVING CIRCUIT.

Application filed August 29, 1924. Serial No. 734,858.

This invention relates to radio receiving circuits and more particularly to tuned radio frequency amplifiers.

One of the principal objects of the invention is to prevent the production of sustained oscillations in a tuned radio frequency amplifier.

A feature of the invention is a vacuum tube amplifier in which the coupling capacity of the tube is neutralized for all frequencies.

A further object is to improve amplifiers of the type wherein the potential of the plate coil is not effective upon the grid coil to produce oscillations.

A feature of the invention is a loop receiver wherein the capacity of the loop to ground is not affected by the position of the loop.

Other objects of this invention will be apparent to those skilled in the art from the following specification and claims.

In a specific circuit embodying the invention, these objects are accomplished by providing a loop aerial tuned by a condenser and loosely coupled to a second tuned circuit by symmetrically placed condensers which may be variable. The mid-points of the loop and the inductance coil of the tuned circuit are grounded and connected to the cathode of a suitable space discharge device or tube which may function as a detector, amplifier, or in the case where a local oscillator is used to produce an inaudible intermediate frequency, as a combining device for the local and received oscillations. The grid of the tube is connected to one end of the tuned circuit. A condenser connected from the anode of the tube to the end of the tuned circuit opposite that connected to the grid serves to neutralize the tendency of the inherent feed-back effect of the tube to produce oscillations. If the anode-grid be considered as one capacity and the neutralizing condenser as another capacity, then the loop circuit, the coupling condensers and the tuned circuit are symmetrically arranged with respect to these capacities. Furthermore, the loose coupling of the loop circuit to the tuned circuit causes the loop circuit to be electrically remote from the space discharge device.

The figure is a diagrammatic representation of a circuit embodying this invention.

In the figure, loop 1 is tuned to the frequency of the incoming signals by condenser 2. A tuned circuit comprising coil 3 and condenser 4, is tuned to this same frequency and coupled to the loop circuit by means of condensers 5 which may be made variable if desired. Tube 6 has its output circuit connected to the primary 7 of a tuned radio frequency transformer, the secondary 9 of which may be connected to a detector or another stage of amplification as desired. The grid of tube 6 is connected to one terminal of coil 3. The filament of tube 6 is connected to the center portion of coil 3 from which point connection is also taken to the midpoint of loop 1 and to ground. The balancing condenser 8 is connected between the plate of the tube 6 and the second terminal of coil 3.

In the operation of this device, when incoming signals are being received, an oscillating current will traverse coil 7. The coil 7 may or may not have sufficient distributed capacity to act as a circuit resonant at operating frequencies, but in either case, oscillations which are induced in coil 7 will produce a variable potential at the plate terminal of this coil. This potential will be applied to the grid connection of coil 3 through the capacity of tube 6 causing the tuned circuit consisting of coil 3 and condenser 4 to oscillate. By the use of condenser 8 connected to the second terminal of coil 3 and the plate of tube 6 any potential which is applied to one end of coil 3 will be applied equally to the other end, as this insures both ends of the coil being at the same potential, no current will traverse the coil due to the potential of coil 7. Incoming signals, however, will cause the coil to oscillate as a whole. This action will be repeated in the output circuit of the tube.

By connecting the two ends of loop 1 to coil 3 through equal condensers 5 equal potentials will be applied to the two ends of the loop in a manner similar to that in which they are applied to the ends of the coil. This will result in the balancing condenser 8 also preventing oscillations being induced in loop 1 by the potential of coil 7.

Where one side of the loop is grounded, as has often-times been the custom, the capacity of the loop to ground will be affected by the position of the loop with respect to

the surrounding objects. For instance, when one side of the loop is in proximity to a body of metal, should the loop be rotated through 180°, the effect will be similar to changing 5 the ground connection to the other side of the loop, thereby changing its capacity to ground, and seriously disturbing the tuning of the circuit. However, by grounding the midpoint of the loop, any object which would 10 affect one side of the loop will equally affect the other side when the loop is rotated through 180°, the capacity will be unchanged, and the tuning will not be disturbed.

Where the connections of coil 3 are not 15 taken from the midpoint, the capacity of the tube can still be balanced by condenser 8 for a given frequency provided the proper ratio in capacity of the condenser to capacity of the tube is found. However, when the frequency is changed, this balance will be disturbed and oscillations transmitted through 20 the tube from coil 7. If balance is obtained in this manner the midpoint connection of the loop would have to be shifted to a corresponding point. This unbalance of the loop 25 would cause the position of the loop to effect its capacity, a feature which this invention particularly aims to avoid. It will be seen that with the connections as shown, a single 30 balancing condenser can be used to neutralize the capacity of the tube on the tuned secondary circuit and also on the loop. At the same time the aerial effect of the loop, that is, the capacity of the loop to ground which would 35 tend to broaden the tuning of a circuit is reduced to a minimum.

It will be seen from the foregoing that 40 there is provided a circuit which is highly advantageous in that it is directional, highly selective, easily tuned and adjusted, and with only slight or no tendency to become self-oscillatory. The principles of the invention are applicable to circuits containing a plurality of tubes following the tube 6 and functioning 45 as detectors, amplifiers, etc., or to only a single tube having telephone receivers in its output circuit.

Although this invention has been shown and described as applied to a particular circuit 50 it should be understood that the invention is of general application and is only limited in accordance with the following claims.

What is claimed is:

1. A radio receiver comprising a space discharge device, including a cathode, anode and control electrode, a tuned circuit containing a loop wave interceptor, a second tuned circuit including an inductance, capacitively coupled to said loop by two con-

densers, and connected to electrodes of said device, said condensers being symmetrically located with respect to said tuned circuits, a condenser of approximately the same capacity as said discharge device connected between the anode of said device and the second 60 tuned circuit for preventing spurious oscillations in the two tuned circuits, and a common ground connection to said cathode and to the respective mid-points of said interceptor and said inductance, whereby said circuits are maintained balanced during the rotation of said interceptor. 70

2. A radio receiving system comprising a tuned loop circuit and a second tuned circuit including a coil coupled to the tuned loop 75 circuit by capacity elements symmetrically located with respect to said circuits, a device having an inherent feed-back effect due to inherent capacity therein connected across a portion of said tuned circuit, a single capacity 80 connected between the output circuit of said device and an electrically opposed portion of said tuned circuit, and a common ground connection to the midpoint of said loop and the midpoint of the coil in said tuned circuit. 85

3. A loop antenna tuned by a condenser and having its midpoint grounded and connected to the cathode of a vacuum tube relay, a tuned circuit having its midpoint grounded and connected to said cathode, variable capacities symmetrically related to the tuned loop and the tuned circuit for coupling the ends of said loop antenna directly to the ends of said circuit, a connection from an end of said circuit to a control electrode of said relay, and a condenser connected from the anode of said relay to the other end of said circuit for preventing spurious oscillations in the tuned loop and the tuned circuit. 95

4. In a radio receiving circuit, a tuned 100 loop circuit, a vacuum tube having input and output circuits, a second tuned circuit including a coil, capacity elements for connecting the ends of said loop to the ends of said coil, means connecting the input circuit of said tube to one end and the electrical center of said coil, a small condenser having approximately the same capacity as the capacity of said tube connected to the anode of the tube and the second terminal of the coil, a 105 tuned circuit connected to the output circuit of said tube, and means connecting the electrical center of said coil and the center of said loop to ground. 110

In witness whereof, I hereunto subscribe 115 my name this 26th day of August, A. D. 1924.

LEWIS M. CLEMENT.
